mesne assignments, of one-fourth to Thad J. Earl,
Defiance, Ohio, and one-half to R-N Acceptance Limited, Calgary, Alberta, Canada, a corporation of Canada

Filed Nov. 21, 1968, Ser. No. 14,583

Term of patent 14 years

Int. Cl. D12—13

U.S. Cl. D14—3

FIG. 1

I claim:

The ornamental design for a refuse vehicle, substantially as shown.
